(57) CLAIM

The ornamental design for the “sole of a shoe for motorcycling”, as shown and described.

DESCRIPTION

FIG. 1 is a perspective view of a sole of a shoe for motorcycling, with inserts;

FIG. 2 is a plan view thereof from above;

FIG. 3 is a plan view thereof from below;

FIG. 4 is a right side elevation view thereof;

FIG. 5 is a left side elevation view thereof;

FIG. 6 is a front view thereof;

FIG. 7 is a rear view thereof;

FIG. 8 is a perspective view of the sole of a shoe for motorcycling, without the inserts;

FIG. 9 is a plan view thereof from above;

FIG. 10 is a plan view thereof from below;

FIG. 11 is a left side elevation view thereof;

FIG. 12 is a right side elevation view thereof;

FIG. 13 is a front view thereof;

FIG. 14 is a rear view thereof;

FIG. 15 is a perspective view of the lateral insert for a sole of a shoe for motorcycling;

FIG. 16 is a plan view thereof from above;

FIG. 17 is a plan view thereof from below;

FIG. 18 is a right side elevation view thereof;

FIG. 19 is a left side elevation view thereof;

FIG. 20 is a front view thereof;

FIG. 21 is a rear view thereof;

FIG. 22 is a perspective view of the rear insert for a sole of a shoe for motorcycling;

FIG. 23 is a plan view thereof from above;

FIG. 24 is a plan view thereof from below;

FIG. 25 is a right side elevation view thereof;

FIG. 26 is a left side elevation view thereof;

FIG. 27 is a front view thereof; and,

FIG. 28 is a rear view thereof.
